UNITED STATES PATENT OFFICE

134,426

DESIGN FOR A PURSUIT AIRPLANE

James S. McDonnell, Jr., Clayton, Mo., assignor
to McDonnell Aircraft Corporation, St. Louis,
Mo., a corporation of Maryland

Application February 18, 1942, Serial No. 105,859

Term of patent 14 years

To all whom it may concern:

Be it known that I, James S. McDonnell, Jr., a citizen of the United States and a resident of Clayton, in the county of St. Louis and State of Missouri, have invented a new, original, and ornamental Design for a Pursuit Airplane, of which the following is a specification, reference being had to the accompanying drawings, forming part thereof,

Fig. 1 is a top perspective view of a pursuit airplane showing my new design,

Fig. 2 is a top plan view,

Fig. 3 is a front elevational view; and

Fig. 4 is a side elevational view.

I claim:

The ornamental design for a pursuit airplane, substantially as shown.

JAMES S. McDONNELL, JR.
